COLLAPSIBLE CONTAINER

John W. Muirhead, 2299 Middle Bench Road, R.R. 1,
Penticton, British Columbia, Canada
Filed May 7, 1962, Ser. No. 192,735
3 Claims. (Cl. 217—47)

This invention relates to collapsible containers which may be flattened out for shipment and storage, and which may be quickly and easily erected for use.

An object of the present invention is the provision of collapsible containers which may be made from scrap materials, such as wood, veneer or plywood, or partly from materials such as cardboard, plastic and the like.

Another object is the provision of a collapsible container construction which makes it possible to make containers of various sizes from substantially the same basic elements.

A further object is the provision of containers having great strength as compared to the strength of the materials used in their construction.

Yet another object is the provision of containers having any number of confining walls, thereby determining the cross sectional shape of the containers, with or without covers.

A still further object is the provision of collapsible containers of simple, attractive and light but strong construction.

A collapsible container according to the present invention includes a plurality of walls. These usually include a bottom wall, two side walls, and a top or cover which is considered a top wall, although in some cases the latter may be omitted. Each wall comprises end battens preferably formed of wood, but which may be formed of plastic or the like, and a plurality of co-extensive slats lying in a common plane. These slats are preferably formed of wood veneer, but they may be made of thin plywood or other suitable material, such as cardboard, plastic and the like. These slats are quite small so that they may be made from scrap veneer or plywood. The battens have grooves in surfaces thereof into which ends of at least some of the slats fit and are secured. The slats are preferably secured in the batten grooves by means of glue since such glue may be as strong as or stronger than the slats themselves, and glue does not split or otherwise weaken the slats. Each wall may be made any desired length with these comparatively small slats by using one or more intermediate battens between and parallel with the end battens. The intermediate battens may be made of the same material as the end battens. Each intermediate batten has grooves in each of opposite surfaces thereof into which ends of the slats fit and are secured, preferably by means of glue. Thus, the length of a container wall may be increased by adding more intermediate battens and slats. The width of each wall is determined by the lengths of the battens, and these have to be cut at predetermined lengths to produce walls of desired widths.

The battens of the container walls are aligned, and flexible hinge means interconnect adjacent ends of the battens so that the walls may be swung from a flat collapsed condition to positions normal to each other to form a container having at least bottom and side walls. The hinge means are preferably pieces of wire extending longitudinally from one batten to the next adjacent batten. Each wire has its ends bent inwardly so that they are pressed into the battens, and it is preferable to apply sufficient pressure against the wire hinges to press said wires into the batten surfaces. Although it is preferable to use short pieces of wire for the hinges, it is to be understood that cloth tape, plastic or other binding material may be used,

2

in which case, it will be preferable to secure the ends of the material to the battens by means of adhesive.

If the container is provided with a top wall, one end of each batten of said top wall is connected by hinge means to the adjacent end of a side wall batten. Suitable means is provided for releasably connecting the other end of each batten of the top wall to the adjacent end of a batten of the other side wall of the container. The releasable fastening means may consist of a wire loop on the end of one batten adapted to extend into a larger wire loop on the adjacent end of another batten. A slight bending of the small loop outwardly relative to the container secures the two loops together.

End walls are removably mounted in the container at the end battens of the walls thereof. Each end wall may be made of such size that it bears against the inner surfaces of the end battens when the container is erected. Suitable means is provided for releasably securing each end wall in position. In the preferred form of container, this securing means preferably is in the form of an elastic band having a clip at each end. Each clip is shaped so that it may be moved through a small hole formed in a slat of one of the walls of the container. The clip is moved from the inside of the container outwardly thereof, and after it is passed through the slat hole, the clip is swung into a position substantially at right angles to the elastic band, at which time, it bears against the outer surface of the slat. As the clips of the elastic band are passed through opposed walls of the container, the band draws said walls towards each other against the adjacent edges of the container end wall. It is preferable to apply each fastener to the side walls of the container near the upper edges thereof.

An example of this invention is illustrated in the accompanying drawings, in which:

FIGURE 1 is a perspective view of the walls of a container laid out flat for shipment or storage,

FIGURE 2 is an enlarged cross section taken on the line 2—2 of FIGURE 1,

FIGURE 3 is a perspective view of an end wall for the container,

FIGURE 4 is a perspective view of the outside of one end of the container in erected position,

FIGURE 5 is a perspective view of the inside of an end of the container with the top wall in the open position,

FIGURE 6 illustrates one form of fastening or securing means for the container,

FIGURE 7 is a perspective view with parts broken away of one end of the container illustrating an alternative form of fastening or securing means therefor, and

FIGURE 8 is a horizontal section taken substantially on the line 8—8 of FIGURE 7.

Referring to the drawings, 10 is a collapsible container made up of walls 12, 13, 14 and 15; 12 and 14 being side walls, 13 a bottom wall, and 15 a top wall. As these walls are identical in construction, one only will be described in detail, and the same numerals are used on corresponding parts in these walls.

Each wall comprises identical end battens 20 and 22, the length of which determines the width of the wall. These battens are rectangular in cross section and are thick enough to be substantially rigid in the wall. Batten 20 has a central groove 24 in and extending longitudinally of its inner wall 25. Similarly, batten 22 has a central groove 27 in and extending longitudinally of its inner surface 28. The wall also includes a plurality of small, thin slats 32 which are coextensive and lie in a common plane. These slats are preferably relatively small so that they can be made from scrap or waste material. The length of each wall of the container depends upon the number of slats 32 that are laid end to end between battens 20 and 22. In the illustrated container, each wall is

made up of three sections 35, 36 and 37. The wall sections are separated from each other by intermediate battens, and in this example, there are two intermediate battens 40 and 41. These battens are parallel to each other and to end battens 20 and 22. The intermediate battens for production reasons, are preferably the same size and shape in cross section as the end battens, but they may be larger or smaller, if desired.

Batten 40 has central longitudinal grooves 45 and 46 in the opposite surfaces thereof, while batten 41 has similar grooves 48 and 49 in its opposite surfaces.

The lengths of the battens 20, 22, 40 and 41 are such that each wall is substantially two slats 32 wide. The ends of slats 32 of wall section 35 are positioned in the opposed grooves 24 and 45 of battens 20 and 40, and are secured in said grooves by means of a suitable adhesive. The ends of slats 32 of wall section 35 are secured in opposed grooves 46 and 48 of intermediate battens 40 and 41. Similarly, the slats 32 of wall section 37 are secured in opposed grooves 27 and 49 of battens 22 and 41. As stated above, it is preferable to use a suitable glue for securing the slat ends in the batten grooves or slots. This secures each end of each slat throughout the entire width of said slat to the adjacent batten. Thus, the battens reinforce the slats and provide a strength in the container wall beyond the normal strength of the individual slats. Furthermore, small pieces of wood, such as scrap or waste wood, are used without limiting the size of the container and without weakening said container.

It is preferable to mitre the ends of the battens, and so the ends of battens 20, 22, 40 and 41 are formed with mitres 52, 54, 56 and 58, respectively.

The adjacent ends of the end battens of container walls 12, 13, 14 and 15 are interconnected by suitable flexible hinge means. In this example, the adjacent ends of battens 20 are interconnected by short pieces of wire 60, the ends 61 of which are bent inwardly and pressed into the adjacent batten surfaces. It is preferable that each wire 60 is pressed into the batten surfaces so that there is little or no projection beyond or outwardly of said surfaces. The adjacent ends of end battens 22, intermediate battens 40 and intermediate battens 41 are interconnected by wires 64, 65 and 66, respectively, in the same manner as battens 20.

The flexible wires or hinges 60, 64, 65 and 66 form simple and effective hinge means for interconnecting the adjacent ends of the battens of the container walls. The hinges are inexpensive and simple to apply, and do not add any material weight or bulk to the container.

Container 10 is erected by swinging walls 12 and 14 into positions substantially normal to wall 13. The adjacent mitred ends of the battens bear against each other to make neat corners for the container and to brace one another. For example, the battens of bottom wall 13 bear against the adjacent ends of the battens of side walls 12 and 14, and resist movement of the latter battens inwardly of the container.

A pair of end walls 70 are provided for container 10. Each end wall is shaped to fit the desired cross sectional shape of the container. The end wall may be formed of plywood, plastic, cardboard and the like, but it is preferably formed as clearly shown in FIGURE 3 in order to utilize scrap or waste material. In this example, each wall 70 is formed of a pair of small slats 72 and 73 secured by glue or other fastening means to another pair of slats 75 and 76 which extend across the first slats. As the illustrated container is substantially square in cross section, end wall 70 is square. This wall is of such size that when it is placed in the container near one end thereof, it fits against the inner surfaces 28 of end battens 22.

Suitable means is provided for releasably retaining the end wall in this position. One form of securing means 78 is illustrated in FIGURE 6. This securing means consists of an endless elastic band 80 having identical clips 82 and 83 at the ends thereof. Clip 82 consists of a

piece of wire bent into a loop 84 through which band 80 extends, and having oppositely extending fingers 85 and 86. Similarly, clip 83 is a piece of wire formed with a loop 88 through which band 80 extends, and having oppositely extending fingers 89 and 90. Each of walls 12 and 13 is formed with holes 92 and 93 adjacent end battens 20 and 22 near the upper edge of said wall when it is in the erected position.

When end wall 70 is moved into position within container 10, clip 82 is turned into alignment with band 80 and moved through hole 92 of side wall 14. After the clip is through the hole, it is turned into a position substantially at right angles to the elastic band so that fingers 85 and 86 bear against the outer surface of the adjacent slat 32. Then clip 83 is turned into a position in line with band 80 and moved through hole 92 of wall 12, after which the clip is swung into a position substantially at right angles to the adjacent wall slat and band 80. The slat holes 92 are so located that band 80 extends across the inner surface of end wall 70 to hold said wall against the adjacent end battens. Another end wall is positioned in the container at the opposite end thereof by means of another fastening means 78.

The top wall 15 may be omitted from the container so that it is an open-topped container or crate. If said wall 15 is provided, as shown, relatively large wire loops 96, 97, 98 and 99 project outwardly from free ends of battens 20, 22, 40 and 41 substantially in line with said battens, and in place of wire hinges 60, 64, 65 and 66. Similarly, free ends of battens 20, 22, 40 and 41 of walls 12 are provided with small wire loops 101, 102, 103, and 104, respectively. With this arrangement, when top wall 15 is swung into the closed position substantially at right angles to side walls 12 and 14, loops 96, 97, 98 and 99 of wall 15 fit over loops 101, 102, 103 and 104 of wall 12. The latter loops may be bent outwardly slightly to hold the former loops in position to retain the top wall in the closed position, or they may be bent sharply outwardly to make a stronger connection between the respective loops.

FIGURES 7 and 8 illustrate an alternative form of securing means 110 for releasably retaining each end wall 70 in position in the container. This securing means includes staples 112 and 113 driven into end battens 20 and 22 of side walls 12 and 14 near the tops of the latter. Staple 112 is preferably driven into the outer surface of batten 20 of wall 12 at 115 and bent around said batten, as clearly shown in FIGURE 8, to provide a loop 116 extending transversely of the container and spaced inwardly from the inner surface of said batten 20. Staple 113 is mounted in the same manner on end batten 20 of wall 14, and has a loop 118 projecting transversely of the container towards loop 116. A suitable tie 120 formed of suitable material, such as rubber, wire, tape, plastic or the like, extends between and is secured to staple loops 116 and 118. This draws walls 12 and 14 towards each other against the adjacent edges of end wall 70, and holds said end wall against the inner surfaces of the end battens of walls 12, 13 and 14.

When it is desired to ship or store container 10, the walls 12, 13, 14, and 15 thereof are moved to the flattened out position shown in FIGURE 1, at which time the container takes up very little space. When it is desired to erect the container, it is only necessary to swing walls 12 and 14 into positions substantially at right angles to bottom wall 13, and to move end walls 70 into position within the container against the adjacent surfaces of the end battens 20 and 22. The end walls are quickly, easily and removably secured in position by means of the securing means 78 in the manner described above. If cover or top wall 15 is used, it is swung down into the closed position and loops 101, 102, 103 and 104 bent outwardly relative to loops 96, 97, 98 and 99 removably to hold the top wall in said closed position.

The container may be quickly collapsed by reversing the above-described procedure.

Although all slats 32 are the same size, containers of different dimensions may be made from these slats. For any particular container, it is only necessary to determine the length of the battens for the walls thereof and to cut the battens accordingly. For a very short container, slats 32 may extend between the end battens. For longer containers, a desired number of intermediate battens are used. Each wall of the container may be only the width of one slat 32 wide, or it may substantially equal the width of two or more slats. Thus, the manufacture of these containers is a comparatively simple matter. The end walls for the container have to be made the right size and shape for a predetermined container.

What I claim as my invention is:

1. A collapsible container including a plurality of identical walls; each wall comprising end battens having grooves in inner surfaces and extending longitudinally thereof, at least one intermediate batten between and parallel with the end battens and having grooves in opposite surfaces and extending longitudinally thereof, and a plurality of co-extensive slats of identical dimensions lying in a common plane and extending between the battens and secured in the grooves thereof; the battens of said walls being aligned, the number of intermediate battens and slats having been selected from stock to produce a container of desired length, flexible hinge means interconnecting adjacent ends of the end and intermediate battens whereby said walls may be swung from a flat collapsed condition to positions angularly arranged relative to each other to form a container having bottom and side walls, end walls removably mounted in the container at the end battens of the walls thereof, and securing means removably retaining each of the end walls against the adjacent end batten, said securing means comprising an elastic band with clips on ends thereof, said clips being adapted to be moved through holes in slats of opposed container walls immediately inside an end wall.

2. A collapsible container as claimed in claim 1 in which each clip comprises a piece of wire bent into a loop through which the band extends, and ends of the wire constitute fingers projecting outwardly in opposite directions from said loop.

3. A collapsible container including a plurality of identical walls; each wall comprising end battens having grooves in inner surfaces and extending longitudinally thereof, at least one intermediate batten between and parallel with the end battens and having grooves in opposite surfaces and extending longitudinally thereof, and a plurality of co-extensive slats of identical dimensions lying in a common plane and extending between the battens and secured in the grooves thereof; the battens of 10 said walls being aligned, the number of intermediate battens and slats having been selected from stock to produce a container of desired length, flexible hinge means interconnecting adjacent ends of the end and intermediate battens whereby said walls may be swung from a flat collapsed condition to positions angularly arranged relative to each other to form a container having bottom and side walls, end walls removably mounted in the container at the end battens of the walls thereof, and securing means removably retaining each of the end 20 walls against the adjacent end batten, said securing means for each end wall comprising staples secured to the end battens of the walls at opposite edges of said end wall, and an elastic tie extending between and secured to said staples and extending over the inner surface of said end 25 wall.
